UNITED STATES PATENT OFFICE.

FREDERICK D. VAN NORMAN AND BYRON F. STOWELL, OF SPRINGFIELD,
MASSACHUSETTS.

DESIGN FOR A METAL PLATE.

SPECIFICATION forming part of Design No. 30,628, dated April 25, 1899.

Application filed December 19, 1898. Serial No. 699,767. Term of patent 7 years.

To all whom it may concern:

Be it known that we, FREDERICK D. VAN NORMAN and BYRON F. STOWELL, citizens of the United States of America, residing at 5 Springfield, in the county of Hampden and State of Massachusetts, have invented and produced a new and original Design for a Metal Plate, of which the following is a specification, reference being had to the accompanying drawing, forming part thereof, which consists of one figure only, showing in plan view a surface having our new design applied thereto.

As shown in the drawing, the leading or material feature of the design consists of a series of undulating or wave-like bands or stripes *a*, extending in substantially parallel lines across the surface of a metal plate *A* in one direction, said bands or stripes being 15 separated by substantially uniform spaces *b*, and a second series of bands or stripes *d*, having similar undulations and separated by

spaces substantially equaling those which separate the said first-named bands or stripes, said second series of bands crossing and at 25 the points of intersection overlying the bands of the said first-named series at substantially right angles. The undulations of said bands are composed of alternating reversed curves, commonly spoken of as "ogee" curves, and 30 the curves of each of said series of bands have uniform radii and uniform spacing between the bands of the different series.

Having described our invention, what we claim, and desire to secure by Letters Patent 35 of the United States, is—

The design for a metal plate as herein shown and described.

FREDERICK D. VAN NORMAN. [L. S.]
BYRON F. STOWELL. [L. S.]
